AUTOMATIC TAIL CLAMP FOR PRESSES

George W. Johnson, Cincinnati, Ohio, assignor to
The American Laundry Machinery Company,
Norwood, Ohio, a corporation of Ohio

Application January 12, 1935, Serial No. 1,491

6 Claims. (Cl. 68—9)

This invention relates to garment presses characterized by pressing members including a padded work-receiving buck having a flexible face. More particularly the invention pertains to means for clamping the work against this face, in position to be pressed, as exemplified by the tail clamp for shirts which is familiar to the art. Such a tail clamp includes a band adjustable between a closed position extending across the face of the buck to hold the work against the latter, and an open position clear of the buck to permit positioning and removal of the work.

Heretofore in the art provision has been made for a clamping motion of the band against the buck as distinguished from the registering of the band over the buck. It is an object of the present invention to eliminate the necessity of such clamping band motion. The invention includes the provision of a clamping member located within the buck cooperative with the band member which is therewithout, and embraces the provision of separate motions for these clamping members by simple means in automatically timed relation.

The exact nature of this invention together with further objects and advantages thereof will be apparent from the following description taken in connection with the accompanying drawing, in which Figs. 1 and 2 are elevation views of an embodiment of the invention, in typical section as to certain of the working parts, Fig. 1 showing these parts as in open position, and Fig. 2 as in closed position; Fig. 3 is a plan view of the same, showing the parts as in open position, and in dot dash lines indicating the closed position of some of them; Fig. 4 is a detail in horizontal section as in the plane of line 4—4, Fig. 1.

With reference now to the drawing, 1 represents generally the buck of a garment press having a base 2 and a table 3. These parts will be recognized as typical in the art, the buck being horizontally disposed to receive the work and being cooperative with a pressing head, not shown but movable on the base 2 relative to the buck.

The buck 1 has a padded face, the padding including as here shown, a number of metallic spring elements 4 and a flexible cover 5 thereover and secured as by the spring straps 6.

For clamping the work upon the face of the buck, that the smooth lay of the work may be maintained during the pressing operation, a pair of clamping members are provided. One of these comprises a band 7 and the other a bar 8.

The band 7 is of metal, thin and narrow, as indicated in the drawing, and as usual in the art.

It is supported upon a frame including a head part 9 to which the rearward end of the band is secured, and a rigidly associated arm 10 to which the forward end of the band is secured. The head 9 is supported by a bracket 11 for swinging adjustment about a vertical axis over the end of the buck between an open position removed from the buck as indicated in Fig. 3, and leaving the latter clear for access by the operator, and a closed position across the buck, as indicated in Fig. 3. The parts are so proportioned and arranged that the band 7 will just freely move over the face of the buck, lying closely adjacent thereto.

Power means are provided for adjusting the band between its two positions. For this purpose the head 9 is secured with a coaxial pinion 12 cooperative with a rack 13. The rack is actuated by a simple fluid motor including a cylinder 14 in which a piston 15 moves, a spring 16 being provided for return of the piston. This fluid motor is controlled by the operator through a handle 17 of a valve which includes a piston 18 controlling the interconnection between a supply of fluid pressure through the line 19, a line 20 leading from the valve to the cylinder 14, and an exhaust outlet 21 for the valve.

By the arrangement described it will be apparent that when the valve 17 is in its outermost position as indicated in Fig. 1, the cylinder 14 will have connection with the atmosphere by way of the line 20 and exhaust outlet 21, so that the spring 16 will maintain the piston 15 with its associated rack 13 at the inner end of its stroke, and the band 7 carried by its frame, in open position. When it is desired that the band be moved to closed position as indicated in Fig. 2, the valve 17 is moved by the operator to the position therein shown, closing the exhaust outlet 21 and admitting the fluid pressure from the line 19 into the line 20 and to the cylinder 14. This moves the piston 15 against the spring 16, actuating the rack 13 and pinion 12 to swing the frame to bring the band 7 to its closed position as shown in Fig. 2.

The bar 8 is preferably located within the padding of the buck 1, that is, it is positioned to be effective upon the inner face of the padding 4. It is disposed to be in registry, crosswise of the buck, with the band 7 when the latter is in closed position.

The bar 8 is adjustable toward and from the band, to be cooperative therewith for clamping effect upon the cover 5 and whatever work may be overlying the latter. For this purpose the bar 55

is supported on a vertically movable rod 22, the bar preferably having pivotal mounting on the rod so that the bar may accommodate itself to the contour of the band 7, with differential effect, to distribute and equalize the clamping pressure.

That the bar 8 may have automatic actuation in timed relation with the band 7, the bar 22 has an associated actuating piston 23 movable 10 in a cylinder 24, which in turn has connection by a line 25 with a port 26 in the side of the cylinder 14. This port 26 is so located that it will be uncovered as the band-actuating piston 15 has moved the band to closed position in 15 registry with the bar 8. A line 27 provides a return connection from the cylinder 24 to the line 20, the line 27 including a check valve 28 arranged to permit flow from the cylinder 24 toward the line 20 but prevent flow in the opposite 20 direction.

Clamping operation of the bar 8, relative to operation of the band 7, will therefore be automatic, as follows: Commencing with the parts in open position as indicated in Fig. 1, admission 25 of pressure to the line 20 by manipulation of the valve 17 will move the band 7 to closed position as already described, having no effect upon the bar 8 during this operation because of the check valve 28. As the band 7 attains closed position, 30 however, its piston 15 uncovers the port 26 admitting fluid pressure through the line 25 to the bar-actuating piston 23. This raises the rod 22 forcing the bar 8 toward the band 7 with the desired clamping effect, which is maintained 35 until shifting of the control valve 17.

To return the parts to open position, this control valve is returned to the position of Fig. 1. The fluid pressure from the cylinder 24 is immediately thereupon exhausted principally by 40 way of the line 27 and check valve 28, line 20 and exhaust outlet 21. A spring 23' may be provided for the purpose if necessary. Coincident with such evacuation of the cylinder 24, evacuation 45 commences in the cylinder 14, the strap band 7 returning to open position, and the band opening motion commencing substantially as soon as the band is released from the clamping effect of the bar 8.

What I claim is:

- 50 1. In a buck having a flexible cover with a work-receiving face, a pair of clamping members disposed on opposite sides of said cover and including a bar on the inside of the cover, and a band outside the cover, means for adjusting said band between an open position clear of said buck and a closed position over said face and in registry with said bar, and means for adjusting said bar toward and from said band when the latter is in said closed position.
- 55 2. In a buck having a flexible cover with a work-receiving face, a pair of clamping members disposed on opposite sides of said cover and including a bar on the inside of the cover, and a band outside the cover, means for adjusting said band between an open position clear of said buck and a closed position over said face and in registry with said bar, and means for adjusting said

bar toward and from said band when the latter is in said closed position, said bar being of substantial length across the buck and arranged to accommodate itself to said band to provide distribution of clamping effect between said clamping members. 5

3. In a buck having a flexible cover with a work-receiving face, a pair of clamping members disposed on opposite sides of said cover and including a bar on the inside of the cover, and a band outside the cover, means for adjusting said band between an open position clear of said buck and a closed position over said face and in registry with said bar, and means for adjusting said bar toward and from said band when the latter is in said closed position, said bar being replaceable relative to said band and mounted for differential movement to be self-accommodating thereagainst.

4. In a buck having a flexible cover with a work-receiving face, a pair of clamping members disposed on opposite sides of said cover and including a bar on the inside of the cover, and a band outside the cover, means for adjusting said band between an open position clear of said buck and a closed position over said face and in registry with said bar, and means for adjusting said bar toward and from said band when the latter is in said closed position, actuating means for said adjusting means and providing for adjustment of said bar toward said band automatically following adjustment of said band to closed position, and release of said bar before opening adjustment of said band. 20

5. In a buck having a flexible cover with a work-receiving face, a pair of clamping members disposed on opposite sides of said cover and including a bar on the inside of the cover, and a band outside the cover, means for adjusting said band between an open position clear of said buck and a closed position over said face and in registry with said bar, and means for adjusting said bar toward and from said band when the latter is in said closed position, actuating means for said adjusting means and providing for adjustment of said bar toward said band automatically following adjustment of said band to closed position, and release of said bar before opening adjustment of said band, said actuating means including a pair of fluid motors one for each clamping member, the band motor having port means and the bar motor being arranged for actuation responsive thereto in closing operation, and valve means providing opening operation of said bar means independent of said port means. 45

6. In combination with a buck having a work-receiving face, a pair of clamping members disposed to be on opposite sides of a stretch of work upon said face, said members comprising a band 60 above said face and a bar therebeneath, means for adjusting said band between an open position clear of said buck and a closed position over said face and in registry with said bar, and means for adjusting said bar toward and from said band 65 when the latter is in said closed position.

GEORGE W. JOHNSON.
